UNITED STATES PATENT OFFICE.

DAVID BICE JAMES, OF SAN FRANCISCO, CALIFORNIA.

MINER'S CANDLESTICK.

SPECIFICATION forming part of Letters Patent No. 410,166, dated September 3, 1889.

Application filed February 2, 1889. Serial No. 298,288. (No model.)

To all whom it may concern:

Be it known that I, DAVID BICE JAMES, a citizen of the United States, residing at San Francisco, county of San Francisco, State of California, have invented a new and useful Miner's Candlestick, of which the following is a specification.

My invention relates to an improvement in miners' candlesticks, the object thereof being to provide a simple and cheap candlestick for use by miners; and it consists in the construction, arrangement, and combination of parts, substantially as will be hereinafter described and claimed.

15 In the annexed drawing the figure shown thereon is a perspective view of my improved candlestick.

In carrying my invention into practical effect I provide a strip of spring metal—such as steel—which is bent backward upon itself, so as to form a loop A at the point where it is bent, which loop is easily adapted to be grasped by the hand of the person using the candlestick, and the steel strip forms also the shorter arm having the slot B and the longer arm having the point E at its extremity and formed with a knife-edge G and also with a notch H. These two arms of the main portion of the candlestick lie alongside of each other. The longer arm is provided with a loop C, which passes through the slot B in the shorter arm, one end of said loop being firmly connected to the long arm, while the other end projects through said arm and is 35 provided with a hooked portion F.

In using my improved candlestick the candle will be inserted in the loop C, with

the shorter arm of the frame pressing against it, so as to hold it firmly within the loop. The knife portion of the longer arm is used for 40 the purpose of cutting fuse and the circular notch is used for the purpose of fastening caps to fuse.

My improved candlestick may be either hung to an object by means of the hook F or 45 it may be stuck into an object by pressing the point E into said object.

Having thus described my invention, what I claim as new, and desire to secure by Letters Patent, is—

1. In a candlestick for use by miners, the spring-metal frame having a slotted shorter arm and the longer arm provided with a knife-edge, in combination with the loop passing through the slotted arm, substantially as described.

2. In a candlestick for miners' use, the spring-metal frame forming the slotted shorter arm, the longer arm having the pointed extremity, a knife-edge, and a circular notch, 60 and the loop connected to the longer arm, passing through the slotted arm, and provided with a hook, substantially as described.

3. In a miner's candlestick, the metal frame bent at A and having the slotted shorter arm, the longer arm pointed at E, having a knife-edge G and notch H, and the loop C, passing through the slotted arm, together with its hooked end F, substantially as described.

DAVID BICE JAMES.
